UNITED STATES PATENT OFFICE.

THEODORE F. MORSE, OF SILVER CREEK, NEW YORK, ASSIGNOR TO HUNTLEY MANUFACTURING COMPANY, OF SILVER CREEK, NEW YORK.

CLEANER FOR SEPARATOR-SCREENS.

1,074,970.

Specification of Letters Patent.

Patented Oct. 7, 1913.

Application filed December 26, 1911, Serial No. 667,597. Renewed March 5, 1913. Serial No. 752,251.

To all whom it may concern:

Be it known that I, THEODORE F. MORSE, a citizen of the United States, residing at Silver Creek, in the county of Chautauqua 5 and State of New York, have invented a new and useful Improvement in Cleaners for Separator-Screens, of which the following is a specification.

This invention relates to improvements 10 in cleaners for screens and has reference more particularly to screens which are commonly used in "side shake" separators having oppositely inclined sides, but the invention is not limited to screens of this 15 particular character.

The objects of this invention are to provide a simple and effective cleaner for removing material from screens that becomes lodged or collected therein, which 20 is compact in construction, easily operated, and so constructed that it will adapt itself to the different positions of screens on which it is intended to operate and can be easily and economically installed in 25 separating machines of standard types.

In the accompanying drawings, consisting of three sheets: Figure 1 is a side elevation of a separating machine provided with cleaners for screens containing and 30 embodying the invention. Fig. 2 is a fragmentary sectional elevation on line 2—2, Fig. 1, on an enlarged scale. Fig. 3 is a fragmentary sectional elevation of the rear bearing for the cleaner shaft. Fig. 35 4 is an end elevation of the separating machine. Fig. 5 is a side elevation of one of the brushes. Fig. 6 is a plan view of the cleaner for the screens and its operating connections. Fig. 7 is a fragmentary sectional elevation, on an enlarged scale, on line 7—7, Fig. 4. Fig. 8 is a fragmentary sectional elevation, on an enlarged scale, on line 8—8, Fig. 4. Fig. 9 is an end elevation, 40 partly in section, of the screen cleaning device.

Like reference characters refer to like parts in the several figures.

The cleaner of this invention is applicable for use with various styles of separating machines in which screens are arranged in different positions relative to each other, but is particularly applicable to that type of grain separators known as the "side shake" separators in which the separating shoe is 50 provided with separating screens or sieves 55

which are oppositely inclined from a common center. The separating machine shown in the drawings is of this type and comprises a frame A from which is suspended a shaking shoe B which is provided with two sets of longitudinally disposed screens C C' arranged one above the other, the screens of each set being inclined downward and outwardly from a common center.

This cleaner comprises a plurality of brushes which are adapted to engage the underside of each set of inclined screens for cleaning the same, and the present invention relates to the means which are employed for supporting the brushes beneath the screens and for moving them back and forth in engagement therewith for cleaning purposes.

In the particular construction shown, 75 D D represent the brushes for cleaning the screens. A plurality of brushes are employed for each screen and these brushes are arranged equi-distant apart underneath the oppositely inclined screens of 80 each set. The brushes for each screen are pivotally mounted on a connecting rod E and for this purpose the back of each brush is provided with a bracket e having an opening e' through which the rod E is 85 adapted to extend. Cotter pins e² in the rod E, at opposite sides of the brackets e, prevent the brushes from moving endwise of the connecting rod. The brackets e may be secured to the backs of the brushes by 90 any suitable means, such as by bolts e³. The arrangement of the brushes on the connecting rods E enables the brushes to conform to any changes or inequalities in the 95 surface of the screens and insures a uniform engagement of the brushes with all parts of the screen during their reciprocation beneath the same. The brushes which engage the under sides of the oppositely inclined screens of each set of screens in 100 the machine are supported in position beneath the screens by a common reciprocating shaft F and for this purpose any suitable connections between the connecting rods E for the brushes and the shaft F 105 may be provided. In the construction shown, yokes G are employed, each having a central journal portion g through which the reciprocating shaft F extends, and end journal portions g' g' for the connecting 110

2 rods E. The yokes are prevented from endwise movement on the reciprocating shaft F by collars g^2 having set screws or other suitable means adapted to securely 5 engage the shaft.

The construction above described is preferred as it is simple and inexpensive, but any other suitable means may be employed for pivotally supporting the brushes 10 for the opposite screens from a common reciprocating support and for pivotally connecting together the brushes for each screen. The number and arrangement of the brushes beneath the screens may be readily varied in 15 accordance with the size and nature of the screens to be cleaned. The brushes for the opposite screens are free to turn relative to each other and to their support, and thus tend to balance each other so as to relieve 20 the supporting shaft from strain due to changes in the position of the screens and the brushes, and to equalize the pressure of the brushes against the screens and permit the brushes for each set of inclined 25 screens to be readily adjusted toward and from the screens.

The reciprocating shaft F is adjustably supported at its opposite ends from the frame of the machine so that it can be raised 30 and lowered relative to the screens for regulating the engagement of its brushes with the screens. For this purpose any suitable construction may be employed. That shown consists of bearing plates H H' each provided with an offset bearing portion h in which the shaft F is slidably journaled and which projects through an opening h' in the frame, this opening being of sufficient size to permit the shaft and its bearing to be 35 raised and lowered on the frame. The bearing plates are secured to the frame by bolts h^2 which extend through vertical slots h^3 in the plates for permitting a vertical adjustment of the plates on the frame, and 40 each plate is provided with a lug or ear h^4 which is connected by an adjusting screw h^5 with a bracket h^6 rigidly secured to the frame. By manipulating the adjusting 45 screws for the bearing plates at opposite ends of the shaft, the shaft may be raised or lowered as desired. The shaft F is suitably keyed in the rear bearing plate H' so as to prevent rotation of the shaft in its 50 bearings.

55 Any suitable means may be employed for producing a reciprocating movement of the brush supporting shaft in its bearings on the frame of the separator. In the construction shown, a toothed rack I is movably 60 mounted in suitable vertical guides i secured to one end of the separator frame adjacent to the ends of the brush supporting shafts F. This rack is adapted to engage a drive pinion K for each brush supporting shaft 65 F. This drive pinion is mounted on one

end of a shaft h which is journaled in a bearing h' on the bearing plate H and is provided with a pinion L which is adapted to engage teeth l formed on the outer end of the brush supporting shaft F. For reciprocating the rack I, a pitman M is provided which is suitably pivoted at one end to a clamp m which is secured to the rack I intermediate of its ends, and the opposite end of this pitman is connected to a crank shaft m' which in turn is connected by suitable gears m^2 and m^3 to the auxiliary shaft N with which separators of this character are commonly provided for shaking the lower or scalping screen of the separator. 70 The auxiliary shaft N is driven from the intermediate shaft O, which in turn is driven from the drive shaft P of the machine, suitable pulley and belt connections being provided for this purpose. By means of the 75 gear connections between the crank shaft m' and the auxiliary shaft N the movement of the rack relative to the auxiliary shaft may be reduced as desired, and by regulating the relative size of the drive pinions K and L, 80 the speed and travel of the brush carrying shaft relative to that of the rack may be likewise still further reduced, as may be desired.

85 In the construction shown, the brushes for each screen are so arranged relative to each other and to the length of the screens, and the relative size of the pinions K and L is such, that in each reciprocating movement of the shaft F the brushes will wipe the entire under surface of the screen. 95

The provision of a single vertical rack, which is common to the drive pinions for each reciprocating shaft, greatly simplifies the construction and enables the employment of a single operative means for reciprocating the cleaning brushes of the different sets of screens, and the device is adaptable for separators having a greater or less number of sets of screens than the separator 100 shown in the drawings. The cleaners and their operative mechanism can be readily secured in position in the frame of the separator without requiring any material change or alteration to be made in the general construction and arrangement of the screens and shaking shoes of the separator. 110

115 The drive pinions L for the reciprocating shafts may be arranged above or below the reciprocating shafts as desired. In the construction shown, in which two sets of screens are employed, the shaft for the cleaner for the upper set of screens is arranged below the drive pinion and has its teeth for engagement with the drive pinion arranged on 120 its upper side, while the shaft for the cleaner for the lower set of screens is arranged above its drive pinion and has its engaging teeth on its under side. This arrangement is merely for convenience in securing the shaft 125 130

in position beneath the screens and may be altered as desired. The opposite ends of the shaft are each preferably provided with a helical groove or thread R which extends 5 through the bearings for the shaft. Any dirt which accumulates on the shaft or in its bearings is forced into the groove as the shaft reciprocates, and the bearings are thus kept clean and the wear thereon greatly reduced. The material which accumulates in 10 this groove may be readily removed from time to time as may be necessary.

The engagement of the brushes with the screens may be regulated by adjusting the 15 bearing plates H H' to raise or lower the supporting shaft as may be desired. The operative connections between the rack I and the front end of the shaft being journaled in the front bearing plate H, are adjustable 20 with the plate and shaft longitudinally of the rack so that the pinions K and L will always remain in operative engagement with the rack and shaft respectively, irrespective of any adjustment of the shaft, and thus no 25 separate adjustment of these pinions will be required in making the adjustment of the shaft.

I claim as my invention:

1. In a separator, the combination of a 30 cleaner for the screens, comprising a plurality of brushes arranged in opposite parallel rows, a supporting shaft centrally located between said rows of brushes, means for pivotally securing said brushes to said shaft, 35 and means for reciprocating said shaft, substantially as set forth.

2. In a separator, the combination of a 40 cleaner for the screens comprising a plurality of brushes arranged in opposite parallel rows, means for connecting together the brushes for each row, a supporting shaft arranged centrally between the rows, means for pivotally securing said brush connecting 45 means to said shaft, and means for reciprocating said shaft, substantially as set forth.

3. In a separator, the combination of a 50 cleaner for the screens comprising a plurality of brushes arranged in opposite parallel rows, a connection for the brushes of each row to which the brushes of that row are independently pivoted to swing toward and from the screen, a supporting shaft arranged centrally between the rows, means for supporting said brush connections from said shaft, and means for reciprocating said shaft, substantially as set forth.

4. In a separator having oppositely inclined screens, the combination of a cleaner 60 for the screens comprising a plurality of brushes for said screens, supporting means arranged centrally between and common to the brushes for the oppositely inclined screens, means for securing said brushes to said supporting means, and means for

reciprocating said supporting means, substantially as set forth.

5. In a separator having oppositely inclined screens, the combination of a cleaner 70 for the screens comprising a plurality of brushes for each screen, a supporting shaft arranged centrally between the oppositely inclined screens, means for pivotally securing the brushes for the opposite screens to said shaft to swing toward and from the screens, and means for reciprocating said shaft, substantially as set forth.

6. In a separator having oppositely inclined screens, the combination of a cleaner 80 for the screens comprising a plurality of brushes for each screen, connections common to the brushes for each screen, a supporting shaft arranged centrally between the oppositely inclined screens, means for pivotally securing said 85 connections to said supporting shaft, and means for reciprocating said shaft, substantially as set forth.

7. In a separator having oppositely inclined screens, the combination of a cleaner 90 for the screens comprising a plurality of brushes for each screen, connecting rods to which the brushes for each screen are pivoted, a supporting shaft arranged centrally between said oppositely inclined screens, yokes centrally mounted on said shaft with their opposite ends in engagement with said connecting rods, and means for reciprocating said shaft, substantially 95 as set forth.

8. In a separator having oppositely inclined screens, the combination of a cleaner 100 for the screens comprising a plurality of brushes for each screen, a support arranged centrally between the opposite inclined screens to which the brushes for each screen are pivotally secured and which is adjustable to move said brushes toward and from said screens, and means for reciprocating said support, substantially as set forth.

9. In a separator having oppositely inclined screens, the combination of a cleaner 105 for the screens comprising a plurality of brushes for each screen, a supporting shaft arranged centrally between the opposite inclined screens to which the brushes for the screens are pivotally secured, bearings for said shaft which are adjustable on the separator frame to raise and lower said shaft, and means for reciprocating said 110 shaft in its bearings, substantially as set forth.

10. In a separator having oppositely inclined screens, the combination of a cleaner 125 for the screens comprising a plurality of brushes for each screen, a supporting shaft arranged centrally between the opposite inclined screens to which the brushes for the screens are pivotally secured, bearings for said shaft which are adjustable on the separator 130 frame to raise and lower said shaft, and means for reciprocating said shaft in its bearings, substantially as set forth.

rator frame to raise and lower said shaft, a rack movably mounted on the separator frame adjacent to one end of said shaft, operative connections between said rack and said shaft which are journaled on and adjustable with one of said shaft bearings, and means for reciprocating said rack, substantially as set forth.

11. In a separator having oppositely inclined screens, the combination of a cleaner for the screens comprising a plurality of brushes for each screen, a horizontal supporting shaft arranged centrally between the opposite inclined screens to which the brushes for the screens are pivotally secured, a vertical rack arranged on the separator frame adjacent to one end of said shaft, operative connections between said rack and said shaft, and means for reciprocating said rack, substantially as set forth.

12. In a separator having oppositely inclined screens, the combination of a cleaner for the screens comprising a plurality of brushes for each screen, a supporting shaft arranged centrally between the opposite inclined screens to which the brushes for the screens are pivotally secured, bearings on the separator frame in which said shaft is movable endwise, those portions of said shaft which engage said bearings being provided with helical grooves, and means for reciprocating said shaft in said bearings, substantially as set forth.

13. In a separator having a plurality of 35 sets of oppositely inclined screens arranged one above the other, the combination of a cleaner for each set of screens comprising a plurality of brushes for each screen and a supporting shaft to which the brushes for 40 each screen are pivotally secured, the supporting shafts for the different sets of screens being arranged one above the other, and means for reciprocating said shafts comprising a vertical rack which is arranged adjacent to one end of said shafts, 45 operative connections between said rack and each shaft, and means for reciprocating said rack, substantially as set forth.

14. In a separator having a plurality of 50 sets of oppositely inclined screens arranged one above the other, the combination of a cleaner for each set of screens comprising a plurality of brushes for each screen and a supporting shaft to which the brushes for 55 each screen are pivotally secured, the supporting shafts for the different sets of screens being arranged one above the other, and means for reciprocating said shafts arranged at one end of said shafts and operatively connected with each shaft, substantially as set forth.

Witness my hand, this 19th day of December, 1911.

THEODORE F. MORSE.
